(57) **CLAIM**

The ornamental design for a power end frame segment, as shown and described.

DESCRIPTION

FIG. 1 is a front perspective view of a power end frame segment;

FIG. 2 is a front view of the power end frame segment;

FIG. 3 is a rear view of the power end frame segment;

FIG. 4 is left side view of the power end frame segment;

FIG. 5 is a right side view of the power end frame segment;

FIG. 6 is a top view of the power end frame segment; and,

FIG. 7 is a bottom view of the power end frame segment.

The broken lines in FIGS. 1 through 7 form no part of the claimed design.

Attached hereto is an Appendix that includes FIGS. A through G. FIGS. A through G in the Appendix form no part of the claimed design.

Although FIGS. A-G form no part of the claimed design, FIGS. A through G depict a power end frame segment that includes the claimed design. FIG. A is a front perspective view of the power end frame segment. FIG. B is a front view of the power end frame segment. FIG. C is a rear view of the power end frame segment. FIG. D is a left side view of the power end frame segment. FIG. E is a right side view of the power end frame. FIG. F is a top view of the power end frame segment. FIG. G is a bottom view of the power end frame segment.

1 Claim, 5 Drawing Sheets
